UNITED STATES PATENT OFFICE.

OSCAR A. YOUNGREN, OF SHERIDAN, WYOMING, ASSIGNOR TO NATIONAL LIFE PRESERVER COMPANY, OF SHERIDAN, WYOMING, A CORPORATION OF WYOMING.

LIFE-PRESERVER.

1,242,752.

Specification of Letters Patent.

Patented Oct. 9, 1917.

Application filed November 15, 1915. Serial No. 61,614.

To all whom it may concern:

Be it known that I, OSCAR A. YOUNGREN, a citizen of the United States, residing at Sheridan, Sheridan county, and State of Wyoming, have invented and discovered certain new and useful Improvements in Life-Preservers, of which the following is a specification.

The present invention relates to life preservers and consists in the combinations and arrangements of parts hereinafter described and particularly set forth in the accompanying claims.

The object of my said invention is to provide a life preserver in the form of a water-proof suit adapted to completely inclose the body of the wearer and to be put on over the clothing, and one which may be readily adapted to float the wearer regardless of weight, and provide means for sustenance during a considerable period, all as will be hereinafter more fully described and claimed.

A further purpose of the invention is to equip the suit with a buoyant substance other than air, in compliance with the requirement, before sanctioning, of the Steamboat Inspection Service of the Department of Commerce; and to that end a suitable buoyant body is appropriately shaped and forms the lining for the garment.

The invention is proposed as an improvement, or further development, of the life preserver disclosed in my United States Patent No. 1,123,058, of December 29, 1914.

The present construction is disclosed by way of illustration in the accompanying drawings, wherein—

Figure 1 shows the manner of wearing the suit and its exterior construction at the front,

Fig. 2 is a central sectional view thereof, with parts in elevation,

Fig. 2a illustrates the collar construction in detail,

Fig. 3 is a transverse sectional view taken on the line 3—3 of Fig. 1,

Fig. 4 a detail perspective view of a portion of the closure frame removed from the garment,

Fig. 5 an enlarged sectional view of the entrance closure frame in applied position, and

Fig. 6 a detailed central sectional view of the foot inclosure.

Referring to the construction in further detail, the suit or garment A is constructed substantially as indicated in Fig. 1, being of one piece, and made of water-proof material, such as rubber cloth, and comprising arms, legs, and a body portion, the legs terminating in foot coverings 1 (see Fig. 6) to receive the feet of the wearer, and the arms in hand covering 2 to receive the hands of the wearer. The said foot coverings are fitted with inner soles or plates 3, of lead or other suitable material; and outer linings, or reinforcing coverings, 4, of two-ply rubberized material, wholly inclose the foot portions 1. Adjustable bands, or strips, 70 are provided around the ankles to retain the foot coverings upon the feet, and each consists of a part 5, having a ring 6 that engages with a snap hook 7, carried by a strap 8, after the manner illustrated in Figs. 1, 2, and 6.

The garment is adapted to be adjusted to the end that the suit may fit the individual wearer, by means of a pair of tapes or cords 10 (see Figs. 2 and 3), by which the body part of the garment is drawn down on the wearer and the suit, therefore, as a whole, shortened. It will be understood that when the garment is in actual use on the person, the buoyant body portion will always tend to move upwardly on the body of the wearer, and if the suit be too large, this tendency to upward crowding would be considerable. It will therefore be seen that drawing in on the two straps 10 at the crotch will tend to draw the body portion of the suit downward and give a better fit.

The only opening in the suit is at the upper end, extending from approximately the top of the shoulders down and across the front in a curved direction. The body portion of the suit at this opening is attached to a metal frame comprising a single curved bar 11 that is secured to the garment at the entrance opening by piping, or in any other approved manner, and a double and curved bar 12 is in like manner secured to the swinging portion at the entrance opening, and is adapted to close down over the bar 11, bringing the same between the members 105 of the bar 12 and thereby forming a com-

pletely water-tight seal, as clearly shown in Fig. 5. The bar 12 is constructed with hub portions 13 that are hingedly mounted on the projecting end portions 14 of the bar 11 (see Fig. 4).

The frame is locked in closed position by means of a pair of clips 11^a, secured to a rod 12^a on the bar 11 (see Fig. 5), and said clips are adapted to engage with suitable hook members 13^a, carried by the double bar 12. No claim is made to this particular form of fastening between bars 11 and 12, inasmuch as various forms of locking devices may be employed with satisfaction.

The frame construction 11 and 12 is shaped substantially as shown in Fig. 1, to rest and fit comfortably upon the shoulders and chest of the wearer. The rear portion of the suit is in one piece, terminating in a yoke 15 that has a turtle neck 16 adapted to fit snugly about the neck of the wearer and prevent the entrance of any water into the garment. Said neck portions 15 and 16 are provided with a plurality of non-elastic strips 17 that serve to prevent endwise stretching of the neck portion when the same is being fitted over the head, but which will permit of sufficient lateral stretching to allow of this fitting in a convenient and easy manner.

The buoyant substance consists of kapoc, or other approved material, suitably contained in pads 18 and 19 of appropriate thickness, and disposed at the back, the sides, and front of the garment after the manner clearly shown in Figs. 2 and 3. The buoyant lining is securely attached to the inner surface of the garment, and tapes, or cords, 18^a connect the lower portions thereof as shown in Fig. 2, and which, when engaging with the wearer, will properly hold the garment in position.

The front section of the buoyant body is divided along the line of the frame bars 11 and 12, and the upper portion 20 thereof is formed continuous with the back portion 18. There is an opening 21 through the body 20 in register with the neck portion, as will be understood. It may be desired to extend the buoyant lining for a distance within the sleeve portions 22, but this is not necessary, however.

A fresh water or other liquid containing receptacle 23 may be attached to the garment by means of the pocket or strap 24, and a tube 25 leads therefrom through a loop 26 adjacent to the neck portion 15, whereby the contents of the receptacle 23 may be taken by the wearer. The head covering accompanying the garment may be constructed after the manner of a hood, as disclosed in my patent above referred to, or a separate head piece 27 (see Fig. 1) may be provided, as preferred.

It is obvious that those skilled in the art

may vary the details of construction and arrangement of parts without departing from the spirit of the invention, and therefore I do not wish to be limited to such features except as may be required by the claims.

Having thus fully described my said invention, what I claim as new and desire to secure by Letters Patent, is:

1. A life preserver comprising a one-piece suit of waterproof material adapted to inclose the body of the wearer from neck to feet and having an entrance opening therein, a closure for said entrance comprising a curved double bar attached to the suit along one opening edge, a curved single bar attached to the suit along the other opening edge and adapted to engage with said double bar and form a water tight joint therewith, and means for holding a buoyant substance in the suit, substantially as set forth. 75

2. A life preserver comprising a one-piece suit of waterproof material having leg portions and adapted to inclose the body of the wearer from neck to feet and having an entrance opening therein, means located within the garment for shortening or lengthening said garment above its waist line to suit persons of different sizes, and means for holding a buoyant substance in the suit, substantially as set forth. 90

3. A life preserver comprising a one-piece suit of waterproof material having leg portions and adapted to inclose the body of the wearer from neck to feet and having an entrance opening therein, a pair of straps located within and connected to the garment near the waist line thereof adapted for shortening or lengthening the garment above its waist line to suit persons of different sizes, and means for holding a buoyant substance in the suit, substantially as set forth. 100

4. A life preserver comprising a one-piece suit of waterproof material adapted to inclose the body of the wearer from neck to feet and having an entrance opening therein, a closure for said opening comprising a frame of horizontally hinged bars, and a buoyant lining for the suit comprising sections secured thereto and divided along the line of the hinged bars, substantially as set forth. 115

5. A life preserver comprising a one-piece suit of water-proof material adapted to inclose the body of the wearer from neck to feet and having an entrance opening therein, the neck engaging portion provided with non-elastic strips preventing stretching in the lengthwise direction but permitting stretching and contracting in the crosswise direction, a closure for the entrance opening, and a buoyant lining suitably secured within the suit, substantially as set forth. 125

6. A device of the character described comprising a pair of hinged parts, one of 130

said parts adapted to hold a flexible sheet in the form of a web, a projecting member on one of said parts, and a lever pivoted on the other part adapted to engage with said member to close the web holding part against the other part and secure the same in locked relation, substantially as set forth.

7. A device of the character described comprising a single bar and a double bar hingedly connected, a projecting member on one of said bars, and a lever pivotally mounted on the other bar, said lever con-

structed to engage with the projecting member to close the single bar between the members of the double bar and secure the same ¹⁵ in locked relation, substantially as set forth.

In witness whereof, I have hereunto set my hand and seal at Washington, District of Columbia, this first day of November, A. D. nineteen hundred and fifteen.
